Attorney.

UNITED STATES PATENT OFFICE.

GEORGE M. GRAHAM, OF CHICAGO, ILLINOIS, ASSIGNOR, BY MESNE ASSIGNMENTS, TO
SUSPENSION STEEL CONCRETE COMPANY, A CORPORATION OF DELAWARE.

REINFORCED-CONCRETE FLOOR AND CEILING.

1,007,557.

Specification of Letters Patent. Patented Oct. 31, 1911.

Application filed October 17, 1907. Serial No. 397,851.

To all whom it may concern:

Be it known that I, GEORGE M. GRAHAM, a citizen of the United States of America, and a resident of Chicago, in the county of 5 Cook and State of Illinois, have invented certain new and useful Improvements in Reinforced-Concrete Floors and Ceilings, of which the following is a specification.

This invention relates to that type of reinforced concrete buildings which constitute the subject matter of my prior Patent No. 865,490 of Sept. 10, 1907; and has for its object to provide a simple and efficient link or tie piece for connecting in a ready and substantial manner the perforated sheet lathing to the skeleton wire center of the aforesaid patented construction and in the formation of floors and other substantially horizontal portions of the building, all as 20 will hereinafter more fully appear.

In the accompanying drawings:—Figure 1 is a section of a reinforced concrete floor having the present improvement applied. Fig. 2 is an enlarged detail sectional elevation.

Similar numerals of reference indicate like parts in the different views.

Referring to the drawings, 1 represents a member of the border frame of round 30 tubing, and around which are wound continuous wrappings of wire to form upper and lower skeleton centers 2 and 3 therefor, which in connection with such border frame constitutes the skeleton reinforcing portion 35 of a reinforced concrete floor or other like horizontal part of the building, as set forth in detail in my aforesaid prior Patent No. 865,490 of Sept. 10, 1907.

4 is a perforated lathing sheet supported 40 a distance away from the upper skeleton wire center 2 by a series of suspension links 5 of varying lengths, in order that the perforated lathing will have an initial dished form as shown, and as set forth in my afore- 45 said patent.

The present improvement relates wholly to the special construction of the above mentioned suspension links, and whereby the engagement of the same with the lath-

ing and the skeleton rod center can be effected in an easy and convenient manner while at the same time preventing subsequent accidental disengagement during the erection of the building, and prior to the application of the cement body forming the 55 floor, by vibration of the tensioned rod center under the weight of the workmen passing over the same in the erecting operation. To such end said links 5 will have a substantially triangular form, having at one 60 side a gap or opening as illustrated in Fig. 2. As so formed an upper half-round eye or loop 6 is provided for engagement over a wire or rod of the skeleton center 2, and said eye or loop in turn will have a free depending end 7 of some length. A lower elongated stirrup portion 8 is also provided for engagement with the lathing 4 through a plurality of openings therein, and said stirrup in turn will have a free upturned 65 end 9 of some length. With the described construction, the free upturned end 9 will be in a vertical plane a distance outside the vertical plane of the downturned end 7, which arrangement has been found to 70 greatly facilitate the introduction of the links into place, as well as prevent the accidental disengagement above referred to.

10 is an intermediate member which connects the respective upper and lower portions of a link 5, together.

Having thus fully described my said invention what I claim as new and desire to secure by Letters Patent, is:—

Means for connecting perforated metal 85 lathing to the skeleton wire centers of reinforced concrete structures, comprising a link having an approximately triangular form one side of the link being open to provide depending and upturned ends respectively, the upturned end being in a vertical plane outside that of the depending end.

Signed at Chicago, Illinois, this 2nd day of October, 1907.

GEORGE M. GRAHAM.
